A. H. DE VOE,
PLAIT FOLDER FOR SEWING MACHINES,
APPLICATION FILED MAR. 6, 1914.

1,135,966.

Patented Apr. 13, 1915.

UNITED STATES PATENT OFFICE.

ALBERT H. DE VOE, OF WESTFIELD, NEW JERSEY, ASSIGNOR TO THE SINGER
MANUFACTURING COMPANY, A CORPORATION OF NEW JERSEY.

PLAIT-FOLDER FOR SEWING-MACHINES.

1,135,966.

Specification of Letters Patent. Patented Apr. 13, 1915.

Application filed March 6, 1914. Serial No. 322,815.

To all whom it may concern:

Be it known that I, ALBERT H. DE VOE, a citizen of the United States, residing at Westfield, in the county of Union and State of New Jersey, have invented certain new and useful Improvements in Plait-Folders for Sewing-Machines, of which the following is a specification, reference being had therein to the accompanying drawings.

10 This invention relates to improvements in plait folders for sewing machines and has for its object to improve the device for like purpose represented by my U. S. patent application, Serial No. 759,826, filed April 15 9, 1913 and to this end I have provided independently controlled levers for giving to the folding and guiding fingers adjustments for effecting varying widths of plaits, and have simplified and strengthened the parts

20 to better meet the requirements incident to machines specially fitted for effecting a given operation at comparatively high speed in connection with factory products.

In the accompanying drawings, which 25 form a part of the specification, Figure 1 is a view in perspective of the improved folding attachment, together with so much of the bed-plate and the stitch-forming and cloth-feeding mechanism of the sewing machine as is deemed essential for a proper understanding of the invention. Fig. 2 an 30 under side view of the folding fingers and elements for effecting their adjustments, detached from the attachment base-plate.

35 Fig. 3 an edge view of Fig. 2, together with a like view of the attachment base-plate.

Referring to the figures, Fig. 1 represents the bed-plate of the sewing machine, 2 and 3 the front and back slide plates respectively, 40 4 the throat-plate, 5 the cloth-presser, 6 the cloth-presser bar, 7 the needle-bar with its attached needles, as 8, 9 the feed-dog and 10 a portion of the head of one form of commonly employed overhanging bracket-arm.

45 11 represents a bracket secured to the head 10 by suitable screws, as 12, (one only of which is shown) the lower arm 13 of said bracket being provided with adjustably secured plates, as 14, to the outer edges of 50 which are secured by suitable screws, as 15, complementary folding blades 16 and 17, the screw 18 acting to secure said plates in given adjustments.

19 denotes a folding guide provided with 55 an arm 20 adjustably secured in the bracket

11 by screw 21 and 22 the attachment base-plate.

23 represents a rib formed integral with and at the under side of the attachment base-plate and terminating at its opposite ends 60 in bearings 24 and 25; and intermediate of said bearings is formed a depending lug 26 into which is suitably secured a stud-bearing 27 on which is mounted the folding and guiding finger adjusting levers 28 and 29. 65

30 denotes a left hand and 31 a right hand folding and guiding finger, each consisting of integrally formed superposed plies suitably riveted to inlying end sections, as 32, thus forming the pockets or comparatively 70 deep grooves, as 33, (one only of which is shown, see Fig. 1) the under ply of each of said fingers being provided with slots, as 34, and reduced end portions, as 35.

36 Into the bearing 24 is secured by screw 75 a bushing 37, and into the bearing 25 is secured by screw 38 a bushing 39, and into the latter is journaled a hollow shaft 40, and into the bushing 37 a hollow shaft 41, and into the latter is journaled a shaft 42, 80 85 and into the hollow shaft 40 a shaft 43, the upper end of the latter being rigidly secured to the finger adjusting blade 44 carrying the screw 45 tracking one of the slots, as 34, of the guiding finger 31, the upper end of the shaft 42 being rigidly secured to the finger adjusting blade 46 carrying the screw 47 which tracks the other of the slots 34 of the guide-finger 31.

48 denotes a crank-arm rigidly secured to 90 the lower end of the shaft 42 and forked at its outer end to receive the pin 49 carried by the adjusting lever 29, the opposite end of the latter carrying a like stud 50 which is embraced by the forked end of the crank- 95 arm 51 rigidly secured to the lower end of the shaft 43.

52 denotes an index blade secured to the adjusting lever 29 by screw 53 and provided with a pinch screw 54 which, when it is desired to secure the adjusting lever 29 in a given adjustment, is caused to pinch the oppositely arranged surfaces of the index blade against the oppositely arranged surfaces of the attachment base-plate, the index 105 55 indicating the different widths of plaits.

The forward end of the folding and guiding finger 30 is operatively connected with the adjusting lever 28 through the screw 55, 110

2
finger adjusting blade 56 rigidly secured to the hollow shaft 40, the latter carrying at its lower end the rigidly secured crank-arm 57 forked to secure the stud 58 carried by 5 said adjusting lever 28, the opposite end of said folding and guiding finger being operatively connected with said adjusting lever by screw 59, finger adjusting blade 60, hollow shaft 41, the latter carrying at its lower 10 end the rigidly secured crank-arm 61 forked to receive the stud 62 carried by said adjusting lever. The adjusting lever 28 is provided with an index blade 63 of like construction and for a like purpose as the index blade 52 secured to the adjusting lever 29.

64 and 65 are complementary swinging arms, each being pivoted at one end upon a stud 66 secured in the attachment base-plate 20 22, their opposite ends being pivotally attached by screws 67 and 68 to the respective guiding fingers 30 and 31 whereby said fingers are held against movement in the direction of their length. The finger adjusting blades 60 and 46 are preferably slightly longer than the like blades 56 and 44 thus effecting adjustments of the fingers 30 and 31 at a slight angle to the line of seam formation.

30 From the foregoing it is to be understood that the adjustment of the folding and guiding finger 30 is effected through the manipulation of the adjusting lever 28 and that the adjustment of the folding and guiding finger 31 is effected through the manipulation of the adjusting lever 29.

Having thus set forth the nature of the invention, what I claim herein is:—

40 1. In a box-plait folder for sewing machines, an attachment base-plate, complementary folding and guiding fingers mounted thereon, and a bracket provided with oppositely arranged folding blades suspended above the bed-plate of the sewing machine, of independently mounted adjusting levers located below said base-plate and operatively connected with said folding and guiding fingers to effect the adjustments of the latter for varying widths of plaits.

50 2. In a box-plait folder for sewing machines, an attachment base-plate, complementary folding and guiding fingers mounted thereon, and a bracket provided with oppo-

sitely arranged folding blades suspended above the bed-plate of the sewing machine, 55 of adjusting levers pivotally mounted on a stud-bearing depending from said base-plate and operatively connected through forked connections with said folding and guiding fingers to effect adjustments of the latter for 60 varying widths of plaits.

3. In a box-plait folder for sewing machines, an attachment base-plate, complementary folding and guiding fingers mounted thereon, and a bracket provided with oppositely arranged folding blades suspended above the bed-plate of the sewing machine, 65 of independently mounted adjusting levers located below said base-plate and provided with index blades overlying the upper surface of said attachment base-plate and operatively connected with said folding and guiding fingers to effect adjustments of the latter for varying widths of plaits.

4. In a box-plait folder for sewing machines, an attachment base-plate, complementary folding and guiding fingers comprising integrally formed superposed plies, and a bracket provided with oppositely arranged folding blades suspended above the bed-plate of the sewing machine, of independently mounted adjusting levers located below said base-plate and operatively connected with said folding and guiding fingers to effect the adjustments of the latter for varying widths of plaits.

5. In a box-plait folder for sewing machines, an attachment base-plate, complementary folding and guiding fingers mounted thereon, and a bracket provided with oppositely arranged folding blades suspended above the bed-plate of the sewing machine, of independently mounted adjusting levers located below said base-plate and operatively connected with said folding and guiding fingers to give the latter adjustments at one angle to each other and to the line of seam formation.

In testimony whereof, I have signed my name to this specification, in the presence of 100 two subscribing witnesses.

ALBERT H. DE VOE.
